UNITED STATES PATENT OFFICE.

JULIUS LARSEN, OF COPENHAGEN, DENMARK, ASSIGNOR, BY MESNE ASSIGNMENTS, TO
LARSEN MACHINES COMPANY, A CORPORATION OF NEW YORK.

SHUTTLE MECHANISM.

No. 927,152.

Specification of Letters Patent.

Patented July 6, 1909.

Application filed November 28, 1906. Serial No. 345,440.

To all whom it may concern:

Be it known that I, JULIUS LARSEN, citizen of the Kingdom of Denmark, and a resident of Silkegade 13, Copenhagen, Denmark, 5 manufacturer, have invented new and useful Improvements in Shuttle Mechanism, of which the following is a specification.

By sewing machines horizontal shuttles have now and then been in use, although the 10 advantages thereby have not been specially great on account of the circumstances, that it was always necessary to give the needle the so-called heart-movement, inasmuch as the needle had to make a stop at the 15 lowest point of its movement in order to give time to the thread to make its loop around the thread. This has occasioned rather complicated mechanism, and by sole-leather work it had the great inconvenience, that the 20 needle by its relatively long stay in the leather prevented the hole from closing up at once.

The present invention concerns a horizontal shuttle, which is so arranged, that it 25 seizes the thread and holds it fast, so that the needle can without stopping go straight down and then again at once straight up, the upper edge of the ring formed shuttle-bed being provided with a horn, that holds 30 onto the thread during the formation of the stitch.

The invention is shown in the accompanying drawing, in which—

Figures 1, 2 and 3 show the shuttle and the 35 upper part of the shuttle box partly in section in three different positions during the formation of the stitch; and Fig. 4 shows the shuttle in the position shown in Fig. 1, but looked at from above.

The shuttle 2 is of the shape shown in Fig. 4, and is provided with a horn 5, the shuttle being rotatably mounted in a fixed shuttle bed 1, which is provided at a point in its periphery with a slanting incision 4, forming a hook, the incision slanting downwardly in the opposite direction to the horn 5. When the needle 8 has reached the lowest point in this movement, the upper thread 7 is caught by the horn 5 of the shuttle, which shuttle rotates clockwise.

The movement of the shuttle will engage the thread with the hook and a continued rotation of the shuttle will carry the bobbin which is placed in the depression of the shuttle through the loop of thread as shown in Figs. 2 and 3.

Having now described my invention, what I claim and desire to secure by Letters Patent, is—

In a sewing machine, a fixed circular shuttle bed, and a shuttle mounted thereon, the shuttle being provided with a horn for engaging the upper thread, and the shuttle bed with an incision forming a hook for engaging and retaining the thread during the movement of the shuttle in one direction, whereby the shuttle is thrown through the loop of the thread, the direction of the hook being opposite to the direction of the horn.

Signed by me at Copenhagen, Denmark, this 13th day of November 1906.

JULIUS LARSEN.
